UNITED STATES PATENT OFFICE

1,993,516

CONTAINER

Benjamin F. Kells, Cincinnati, Ohio, assignor to
 Container Corporation of America, Chicago,
 Ill., a corporation of Delaware

Application September 29, 1933, Serial No. 691,468

9 Claims. (Cl. 229—37)

The present invention relates to shipping containers and more particularly to shipping containers for electric storage batteries and the like.

5 One object of the present invention is to provide a box or container of the class described which can be economically manufactured and readily assembled for use.

Another object is to provide a container of the 10 class described which is provided with prismatic shaped cushioning members adjacent one end thereof that serve to protect the contents.

A further object of the invention is to provide a container having tubular prismatic shaped 15 cushioning members adjacent one end thereof that also serve as means whereby the container can be handled with facility.

A further object is to provide economical 20 cushioning members for a container of the class described which are readily formed as a part of the container.

A still further object is to provide means for 25 opening the container for inspection and reclosing it with the original unbroken sealing means.

To these and other ends the invention resides in certain improvements and combinations of parts, all as will be hereinafter more fully described, the novel features being pointed out in 30 the claims at the end of the specification.

In the drawing:

Fig. 1 is a perspective view of a set up and sealed container illustrating one embodiment of the invention;

35 Fig. 2 is a cross sectional partial end view of a container illustrating another embodiment of the invention; and

Fig. 3 is a plan view of the general design of blank from which the containers shown in 40 Figs. 1 and 2 are formed.

Similar reference numerals throughout the several views indicate the same parts.

The present invention is directed toward a container that finds particular adaptability for 45 the shipment of electric storage batteries that require considerable protection for their terminals during shipment and which must necessarily always remain in an upright position. The container in its preferred embodiment comprises 50 a blank of suitable fibre board which is scored to provide walls and bottom and top closure flaps, portions being carried on the upper edges of two opposed walls which are capable of being folded to form tubular prismatic cushioning 55 members that lie adjacent the top closure flaps

of the container and effectively protect the contents of the container from damage. These cushioning members further serve as hand holds or means whereby the container can be conveniently carried, as well as serving to facilitate the storing and shipping of the container in an upright position.

5 It is considered preferable to bind or seal the container for shipment with a metal band that can be removed for inspection of the contents 10 and then replaced. In order to facilitate the removal of the band a removable spacing element may be provided which lies between the cushioning members and causes a loosening of the metal band when it, the spacing element, is removed, 15 all as will be more fully described as the description proceeds.

Referring more particularly to the drawing there is shown at 10 in Fig. 3 a view of the blank 20 from which the container shown in Fig. 1 is constructed.

The blank 10 is cut and scored to provide side walls 11 and 12, and end walls 13 and 14. Side wall 11 carries a sealing flap 15 which is adapted to be secured to end wall 14 when the container is set up. Bottom closure flaps 16, 16 and 17, 17 are carried on the bottom edges of side walls 11 and 12, and end walls 13 and 14, respectively. Top closure flaps 18, 18 are carried on the top edges of end walls 13 and 14. The 30 flaps 18, 18 are, in the present instance, of a length substantially equal to the length of the container but, of course, can be of any desired length. The side walls 11 and 12 carry flaps 19, 19 on their upper edges, said flaps being in 35 the present instance scored transversely along the lines 20, 20 and 21, 21, dividing them into sections 22, 22; 23, 23; and 24, 24.

When it is desired to assemble the blank 10 into a container it is first preferably folded into 40 tubular form and the flap 15 is secured to end wall 14 by means of metal staples or other suitable securing means. The end closure flaps 16 and 17 are then folded inwardly to close the bottom of the container and may either be left loose or secured together as deemed desirable. After the storage battery or other article is inserted within the container the flaps 18 are folded inwardly to close the open top of the container. The flaps 19 are then bent inwardly along the 50 score lines 20 and 21 until the sections 22 extend backwardly beneath the sections 24 and substantially abut the juncture between sections 24 and side walls 11 and 12, respectively. The thus folded flaps 19 are then folded inwardly to lie 55

against the upper surface of top closure flaps 18 thereby forming prismatic shaped cushioning members for the top of the container, as shown in Figs. 1 and 2. A metal band 25, such as is in common use, is then secured around the folded flaps 19, the side walls 11 and 12, and the bottom of the container and the same is ready for shipment.

In the present instance the cushioning members are scored so as to form three sided hollow prismatic members which when folded in place form a peak at the center of the container. This effect is quite desirable as it prevents the container from being placed in an upside down position. Of course, if it is desired the flaps 19 can be readily scored to provide prismatic cushioning members with more than three sides which tend to serve the same purpose as the embodiment illustrated.

If it is considered desirable the sections 22 and 24 can be made of such length that the sections 23 do not abut each other when the container is set up as is shown in Fig. 2 but rather are spaced apart as is shown in Fig. 1; when they are so spaced apart a spacing element 26 preferably made of wood and of substantially the same dimensions as the space between the said sections 23 is loosely inserted therebetween before the metal band 25 is applied to seal the container.

The strip or spacing element 26 serves to further reinforce the top of the container as well as to facilitate the removal of the band 25 for inspection of the contents. The removal of the band 25 is accomplished by forcing the strip 26, which is held in place solely by frictional contact with the sections 23, out from between said sections thereby causing the band 25 to loosen up and be easily removed.

It will be understood that while the side and end walls of the container have been positively named as such that the designation is purely relative and that the side walls could just as well be termed end walls and vice versa.

It will be readily apparent that there has been provided an efficient cushioned shipping container that can be easily manufactured from a minimum amount of material; the cushioning means, being preferably hollow, serving as an effective handle for carrying the filled container as well as protection for the contents against rough handling during shipment or storage.

While the present description sets forth a preferred embodiment of the invention, certain changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A box of the character described comprising bottom, side and end walls, end wall flaps on the upper ends of said end walls adapted to fold inward at the open top of said box, hollow prismatic shaped portions integral with said side walls and adapted to lie against said end wall flaps when in closed position whereby cushioning means is provided for the top of said box, a separate removable spacing element disposed between and abutting said prismatic shaped portions, and binding means secured around said sides, top and

bottom and cooperating to hold said spacing element and said box in assembled position.

2. A box of the character described comprising bottom, side and end walls, end wall flaps on the upper ends of said end walls adapted to fold inward at the open top of said box, side wall flaps on the upper ends of said side walls, score lines transversely of each of said side wall flaps whereby said side wall flaps are adapted to be folded to form prismatic shaped cushioning means for the top of said box, a separate removable spacing element disposed between and abutting said prismatic shaped portions, and binding means secured around said sides, top and bottom and cooperating to hold said spacing element and said box in assembled position.

3. A box of the character described comprising bottom, side and end walls, end wall flaps on the upper ends of said end walls adapted to fold inward at the open top of said box, hollow prismatic shaped portions integral with said side walls and adapted to lie against said end wall flaps when in closed position whereby cushioning means is provided for the top of said box, binding means secured around said sides, top and bottom, and removable spacing means disposed between and abutting said prismatic portions and adapted to facilitate the removal of said binding means, said spacing means consisting of a wooden strip.

4. A box of the character described comprising bottom, side and end walls, end wall flaps on the upper ends of said end walls adapted to fold inward at the open top of said box, side wall flaps on the upper ends of said side walls, score lines transversely of each of said side wall flaps whereby said side wall flaps are adapted to be folded to form prismatic shaped cushioning means for the top of said box, binding means secured around said sides, top and bottom, and removable spacing means disposed between and abutting said prismatic portions and adapted to facilitate the removal of said binding means, said spacing means consisting of a wooden strip.

5. A box of the character described comprising bottom, side and end walls, end wall flaps on the upper ends of said end walls adapted to fold inward and form a closure for said box, peaked cushioning means for the top of said box, said cushioning means comprising a pair of hollow triangular shaped cushions, each of said cushions being integral with one of said respective side walls, said triangular cushions having sides substantially abutting each other centrally of the top of the box, and having other sides resting flat against and above said closure.

6. A box of the character described comprising bottom, side and end walls, end wall flaps on the upper ends of said end walls adapted to fold inward and form a closure for said box, extended flaps on the side walls scored and folded to form triangular cushions, one side each of said triangular cushions resting flat upon and above the infolded end wall flaps, sides of said triangular cushions adjacent said last mentioned sides being substantially in contact with each other centrally of the top of the box, and the remaining sides of said triangular cushions being inclined to the plane of the closure, whereby peaked cushioning means is provided at the top of the box.

7. A box of the character described comprising bottom, side and end walls, end wall flaps on the upper ends of said end walls adapted to fold inward and form a closure for said box, peaked cushioning means for the top of said box, said cushioning means comprising a pair of hollow

- triangular shaped cushions, each of said cushions being integral with one of said respective side walls, said triangular cushions having sides substantially abutting each other centrally of the 5 top of the box, and having other sides resting flat against and above said closure, and binding means secured around said sides, top and bottom and cooperating to hold said box in assembled relation.
- 10 8. A box of the character described comprising bottom, side and end walls, end wall flaps on the upper ends of said end walls adapted to fold inward and form a closure for said box, extended flaps on the side walls scored and folded to form triangular cushions, one side each of said triangular cushions resting flat upon and above the infolded end wall flaps, sides of said triangular cushions adjacent said last mentioned sides being substantially in contact with each other centrally of the top of the box, and the remaining 15 sides of said triangular cushions being inclined to the plane of the closure, whereby peaked cushioning means is provided at the top of the box, and binding means secured around said sides, top and bottom and cooperating to hold said box in assembled relation.
- 15 9. A box of the character described comprising bottom, side and end walls, end wall flaps on the upper ends of said end walls adapted to fold inward and form a closure for said box, extended flaps on the side walls scored and folded to form triangular cushions, one side each of said triangular cushions resting flat upon and above the infolded end wall flaps, a separate removable spacing element disposed between said triangular cushions and abutting sides of said triangular cushions adjacent said last mentioned sides, 20 and the remaining sides of said triangular cushions being inclined to the plane of the closure, whereby peaked cushioning means is provided at the top of the box, and binding means secured around said sides, top and bottom and cooperating to hold said box in assembled relation.
